His Attorney.

UNITED STATES PATENT OFFICE

ELMER D. McARTHUR, OF SCHENECTADY, NEW YORK, ASSIGNOR TO GENERAL ELECTRIC COMPANY, A CORPORATION OF NEW YORK

HIGH FREQUENCY DETECTOR

Application filed April 19, 1929. Serial No. 356,535.

The present invention relates to high frequency detectors of the electric discharge type, and more particularly to detectors for ultra-high frequencies above the range in which the triode or three-element electric discharge device is useful, that is, in the range about 3 meters (100 megacycles) and below.

A form of highly evacuated electric discharge device having a hot cathode mounted between two anodes in a strong magnetic field parallel to the axis of the anodes, has been adapted by suitable circuit and control means in an oscillation generator for the production of undamped and modulated wave signals in the range of frequencies which could not be produced by the ordinary triode in a feed back circuit. A generating circuit and means of this character is shown and described in a copending application of Kinjiro Okabe, Serial No. 285,008, filed June 13, 1928 and assigned to the same assignee as the present application.

In order to be useful, however, such signals must subsequently be detected and received, and heretofore many attempts have been made to receive signals of such high frequency, in the range below three meters or above 100 megacycles for example, without altogether satisfactory results. At such high frequencies or low wave lengths the triode or three-element discharge device cannot be made to oscillate satisfactorily in a feed back circuit. Furthermore, the triode is very unstable at such high frequencies and is difficult to operate.

It is therefore the object of my invention to provide an improved detector for undamped and modulated wave signals, and in carrying out my invention I have found that a magnetically controlled electric discharge device of the type above mentioned having a split anode may be used as a heterodyne detector of both types of signals.

My invention will be better understood from a consideration of the accompanying drawing and the description thereof, and its scope will be pointed out in the appended claims.

In the drawing the figure is a wiring di-

agram of a detector embodying my invention.

Referring to the drawing, 5 is a magnetically controlled electric discharge device having a split anode, the anodes or sections 55 of which are indicated at 6 and 7, and together surround a filament or cathode 8 which at its ends is connected with a cathode heating means or source of energy represented by a battery 9, in circuit with which is connected a variable control resistor 10 for varying the temperature of the cathode or filament. Surrounding the device is a field winding 11 which is excited from any suitable source of energy represented by a battery 12, in circuit with which is connected a variable resistor 13 for controlling the excitation or strength of the field whereby the sensitivity of the circuit is controlled as will hereinafter be mentioned. The anodes 6 and 7, which may be considered to be two portions of a split cylinder, are connected with the terminals of an oscillatory circuit 14 comprising suitable tuning means such as a fixed inductance 15 and a variable capacitor 16.

Signals to be received are introduced into the tuned circuit 14 from any suitable source and by any suitable means, and in the present example are introduced into the circuit through a coupling coil 17 inductively 80 coupled with the winding or inductance 15. The coupling coil is in turn connected with a suitable collector of radio frequency energy represented by an antenna 18 and a ground connection 19.

The tuned or oscillatory circuit 14 may be tuned by other means than that shown in the present example and may comprise any suitable elements for causing the circuit to be tunable over a band of frequencies which are to be received. In any case however, it is provided with a mid tap or alternating current center or neutral point indicated in the present example at 20 on the coil of inductance 15. The neutral point is connected with a lead 21 which returns to the cathode at any suitable point such as at 22. In this lead is placed a source of voltage and energy 95 23 for exciting the anodes, and an output

device 24 of any suitable type. In the present example this output device is shown as being a transformer, the primary of which provides an audio frequency impedance in the return lead, and the secondary of which is connected with a suitable receiving means such as a pair of telephone receivers 26.

The signal introduced into the tuned circuit 14 from the antenna system is there made to beat with a locally generated oscillation of a definite frequency provided by the electric discharge device, which is determined by the adjustment of variable condenser 16. As a result there flows in lead 21 between the cathode and the oscillatory circuit an audio frequency component of current which is proportional to the impressed signal.

To make use of this audio frequency current a large reactance or impedance is placed in series with this lead, the impedance in the present example being the primary of transformer 24. By a proper design, this impedance may be made to act like a filter in that it divides the audio frequency component of the current flowing in lead 21 from the radio frequency component. The radio frequency component may be made to flow to the cathode through a suitable by-pass condenser 25. The audio frequency voltage built up across impedance 24 is then transferred to an indicating device which in the present example is a pair of telephone receivers 26 connected with the secondary of transformer 24.

It will be apparent that if the amplification obtained in transformer 24 is insufficient to produce loud signals in telephones 25 or other suitable output device, any suitable additional amplification may be provided by suitable means.

I am aware that electric discharge devices of the magnetically controlled type have been used before in high frequency apparatus and that attempts have been made to use them as oscillating detectors, but heretofore they have been subject to the same difficulties as were three-element electric discharge devices or triodes in that the feed back oscillation producing means introduced difficulties in maintaining constant oscillations at high frequencies or ultra-high frequencies and the strength of the oscillations was below useful values at such frequencies.

I have discovered however, that by using a magnetically controlled electric discharge device of the type described with the anode divided into two equal parts, or a split anode, I obtain an oscillating detector which does not have high internal capacity as compared to the triode and which will receive undamped wave signals or modulated wave extremely high frequency signals, for example wave lengths below one meter.

The essentials of my detector circuit are

few and include merely a magnetically controlled split anode electric discharge device, a tuned oscillatory circuit in connection therewith, the circuit having a tapped neutral point, and an output device providing an impedance to the modulation or beat frequency signals, resulting from detection, in the lead from said neutral point. The impedance is usually an audio frequency impedance for the audible reception of the signals.

By-pass condensers and a plurality of choke coils in supply leads as used with ordinary triodes and the like at high frequencies are not required with this split anode circuit for the reason that the audio frequency or output circuit is connected with the mid tap 20 or alternating current center or neutral point of the oscillatory circuit, hence there is no tendency for conductive coupling between this circuit and others and the need for filter chokes and by-pass condensers to prevent it. Furthermore in the absence of a control grid the use of the usual blocking and by-pass capacities are obviated.

By-pass condenser 25 may be omitted but is desirable as a low resistance path for the radio frequency currents. The circuit employed is very simple and may be reduced to the bare essentials above mentioned and as indicated in the drawing. No grid-leak or condenser or bias voltages are required for detector operation with their corresponding losses and influence upon signals. The circuit is therefore much quieter in operation for the reason that these elements as found in ordinary regenerative receiving circuits are omitted.

A further advantage of the split anode magnetically controlled electric discharge device as a detector of high frequency signals lies in the fact that there is no regeneration to control when changing from telegraphic or undamped wave signals to modulated wave or broadcast signals. The sensitivity may however, be controlled by varying the field strength of the device between certain limits. These limits lie within a range any value of which would produce cut-off or stop the current flow were the anodes connected together for operation as a single anode.

While it may be used with any oscillation frequency desired, a detector circuit substantially as shown in the drawing has been found to function with great stability and to be particularly useful at frequencies at which the three electrode tubes cannot be made to function. This is in the range of frequencies above 100 megacycles (3 meters). It is believed that one of the reasons for the failure of the triode at such frequencies lies in the difficulty experienced in obtaining the "local" oscillations which are necessary for the reception of continuous wave telegraph signals.

A split anode magnetically controlled electric discharge device has been found to operate successfully in producing strong oscillations up to 400 megacycles (0.75 meters).

6 Such oscillations may be brought up to the order of amperes, if necessary, hence a strong output may be maintained.

What I claim as new and desire to secure by Letters Patent of the United States, is,—

10 1. In combination, a magnetically controlled electric discharge device having a split anode, a tuned oscillatory circuit connected therewith and provided with a center tap, a cathode lead connected to said center tap, and an output device and a source of energy connected in said cathode lead.

15 2. In a receiving circuit for high frequency signals, means for detecting said signals including a magnetically controlled electric discharge device having a split anode, means for impressing the signals to be detected between the sections of said split anode and means for receiving the detected signals from said magnetically controlled electric discharge device.

20 3. In combination, an electric discharge device having a divided anode, a cathode, means for producing a magnetic field between said cathode and anode, an oscillatory circuit having its terminals connected with said divided anode and having a center tap, a lead connecting said center tap and said cathode, a source of energy and an impedance in said cathode lead, and means connected with said impedance for receiving detected signals.

25 4. In combination, an electric discharge device having a divided anode, a cathode, means for producing a magnetic field between said cathode and anode, an oscillatory circuit having its terminals connected with said divided anode and having a center tap, a lead connecting said center tap and said cathode, a source of energy and an impedance in said cathode lead, means connected with said impedance for receiving detected signals, and means for varying the strength of the magnetic field between predetermined limits.

30 5. In combination, an electric discharge device having a divided anode, a cathode, means arranged to produce a magnetic field between said cathode and anode, an oscillatory circuit having its terminals connected with said divided anode and having a center tap, means arranged to apply high frequency signals to said circuit, a lead connecting said center tap and said cathode, a source of energy and an impedance in said cathode lead, means connected with said impedance to receive detected signals, and means arranged to vary the strength of the magnetic field between predetermined limits to vary the sensitivity of said circuit to signals.

35 6. A means for detecting undamped and

modulated waves of a frequency higher than 100 megacycles, said means including a magnetically controlled electric discharge device having a split anode and a cathode, a tuned oscillatory circuit connected with said anode and provided with a neutral point, and an output device including an impedance connected in circuit with said neutral point and the cathode.

7. The combination in a carrier wave detector, of an electron discharge device having a cathode, a pair of anodes arranged adjacent said cathode, means for producing a magnetic field between said anodes, means for impressing a signal modulated carrier wave between said anodes whereby the signals with which said carrier wave is modulated are detected by said discharge device, and means connected to receive the detected signals from said discharge device.

75 8. The combination in a carrier wave detector, of an electron discharge device, having a cathode and a plurality of anodes, a circuit connected between said anodes tuned to the frequency of the carrier wave to be detected, means for producing a unidirectional magnetic field between said anodes and cathode, means for impressing a received carrier wave upon said tuned circuit, and means connected with said discharge device to receive the detected signals.

90 9. The combination in a carrier wave detector, of an electron discharge device having a cathode and a plurality of anodes, a circuit connected between said anodes tuned to the frequency of the carrier wave to be detected, means for producing a magnetic field between said anodes and cathode, means for impressing a received carrier wave upon said tuned circuit, and means connected to respond to the space current in said discharge device.

In witness whereof, I have hereunto set my hand this 18th day of April, 1929.

ELMER D. McARTHUR.
